Virgil W. Waller

John L. Haddens

United States Patent Office.

JOHN L. HADDEN, OF PHILADELPHIA, PENNSYLVANIA.

Design No. 2,597, dated March 19, 1867.

DESIGN FOR A WATER COOLER.

The Schedule referred to in these Letters Patent and making part of the same.

TO ALL WHOM IT MAY CONCERN:

Be it known that I, JOHN L. HADDEN, of the city of Philadelphia, in the State of Pennsylvania, have invented or produced a new and original Design for a Portable Water Cooler, of which the following is a full, clear, and exact description, reference being had to the accompanying drawing, making a part of this specification.

The nature of this design consists in giving to the whole exterior of a water cooler a corrugated or fluted appearance.

Referring to the drawing, A is the cylindrical body of the cooler; B the flared base; and C the tapering cover. The body A is formed so as to produce the vertical flutings $a' a'$, as shown in the said drawing. The flared base B is formed so as to present the transverse flutings $b' b'$, as shown. The tapering cover C is formed so as to present the two series of flutings around the same, as shown at $c' c''$.

Having thus described and shown my new design for a portable water cooler, what I claim as my invention or production, and desire to secure by Letters Patent, is—

The design for a portable water cooler, herein set forth.

JOHN L. HADDEN.

Witnesses:

ARTHUR MAGINNIS,
VIRGIL W. WALTER.
